UNITED STATES PATENT OFFICE.

WILLIAM B. BOLLES, OF MILWAUKEE, WISCONSIN.

ANTIPANIC LOCK-OPERATING MECHANISM.

Application filed December 31, 1923. Serial No. 683,537.

To all whom it may concern:

Be it known that I, WILLIAM B. BOLLES, a citizen of the United States, residing at Milwaukee, in the county of Milwaukee and 5 State of Wisconsin, have invented a certain new and useful Improvement in Anti-panic Lock-Operating Mechanism, of which the following is a full, clear, and exact description.

10 This invention relates to anti-panic lock operating mechanisms such as used in connection with doors, more particularly exit doors from theatres, halls, schools and other public buildings.

15 The present invention is an improvement over the lock actuating mechanisms disclosed in my prior Patents 1,383,973 and 1,383,974, granted July 5, 1921, and the mechanism disclosed in my co-pending application Serial No. 572,178, filed July 1, 20 1922.

It is sometimes desirable in order to prevent unnecessary strains and wear upon the lock mechanism and lock operating mechanism that the door locks at times be rendered entirely inoperative so that the doors may swing freely.

It is an object of the present invention to provide means associated with the operating mechanism by which the operating mechanism may be positively held in a position in which the locks are released. In applying the casing of the lock actuating mechanism to a door the casings are not 35 always placed in exactly the same position. In order to compensate for such variations, the stop device employed in accordance with the present invention to secure the lock operating mechanism in its lock releasing position is made adjustable so that regardless of variations in the positioning of the mechanism upon the door, the stop device may be adjusted to a proper position for securing the lock in inoperative position.

40 A further object of the invention is to provide a cushioning device for the actuating lever of the door operating mechanism for cushioning the movement of the lever in either direction to prevent injury to the lever and to the parts of the lock and to prevent injury to the stop when the lever is moved in a direction to move the lock actuating member against the stop.

45 With the above and other objects in view, the invention may be said to comprise the device in its various modifications as illus-

trated in the accompanying drawings, hereinafter described and particularly set forth in the appended claims, together with such variations and modifications thereof as will 60 be apparent to one skilled in the art to which the invention appertains.

Reference should be had to the accompanying drawings forming a part of this specification in which Fig. 1 is an elevation showing a door equipped with locking bolts and operating mechanism for the same; Fig. 2 is an elevation of the mechanism by which the bolts are operated; Fig. 3 is a side elevation with portions in section of the construction shown in Fig. 2; Fig. 4 is a side elevation with parts broken away and shown in section of a modified form of the invention in which the lock actuating mechanism is shown applied to a 70 mortised door lock; Fig. 5 is a vertical section in a plane parallel with the door through the casing of a modified form of actuator for operating bolts carried by the door and co-operating with detention devices in the floor and upper stop of the door casing; Fig. 6 is a sectional detail view showing the upper end of the upper locking bolt in the inmodification shown in Fig. 5.

Referring to the drawings, 1 indicates a door, 2 and 3 indicate locking bolts for the door which cooperate with suitable detention devices carried in the door frame and by the floor adjacent the bottom of the door. Either formed integrally with these latches 90 or secured thereto, are rods 4 and 5. These rods are secured to sliding members 6 and 7 which are guided for vertical movement within the casing 8 which is secured to the inner face of the door as indicated in Fig. 1. 95

The slide 7 is provided with an extension 7^a at its upper end and the slide 6 is provided with a recess or socket portion 6^a in which the extension 7^a fits. The recess 6^a contains a compression coil spring 9 and the extension 7^a engages with the lower end of the spring so that when the slides 6 and 7 are moved toward each other, the spring is placed under compression, which compression serves to restore the members 6 and 7 to their normal position when the pressure which holds the spring 9 compressed is released.

For the purpose of joining the slides 6 and 7 so that they may be moved simultaneously in opposite directions, I employ a pivoted lever 10 which is pivoted at its cen-

ter to the casing and is provided at its ends with upstanding pins 11 and 12. The members 6 have an extension 6^b which is provided with a pin 6^c, this extension being preferably provided with a part 6^d which engages with a wall of the casing 8 so that as the member 6 and the part 6^b and 6^d are moved the bearing of the portion 6^d will serve to take a part of any thrust and assist in guiding the members 6 and 7 in a linear direction.

A link 13 is connected with the pins 6^c and 11 for transmitting movement from the lever 10 to the slide 6. The member 7 is provided with an extension 7^b that may have a part 7^c that engages with the wall of the casing to assist in guiding the slide. The extension 7^b is provided with a pin 7^d and a link 14 connects the pin 12 on the lever 10 with a pin 7^d of the slide 7. Upon the casing there is pivoted a lever 15 which is provided with a rearwardly extending portion 15^a which extends into the casing to actuate the slides. Above the lever there is a portion of the casing indicated at 22 which serves as a guard for the pivot of the lever 15 so as to prevent the hand or clothing of the operator from becoming caught behind the lever. The extension 15^a of the lever 15 extends into and occupies an opening 7^f which is formed in the member 7, the member 15^a normally engaging with the top portion of said opening.

Below the opening 7^f the member 7 is provided with a recess 7^g, mortised out, into which an extension 13^a at the lower end of the link 13 extends. The lower end of the link 13 is preferably provided with a roller 18 to provide a rolling contact on the wall of the casing 8 and to provide a backing for the lower end of the link 13.

With the members of the mechanism arranged as just described, if the operating lever 15 be raised the part 15^a thereof is depressed, which moves the projection 13^a downwardly in the recess 7^g, in turn carrying the link 13 downwardly which communicates its motion to the slide 6, causing the same to be moved into the casing. The downward movement of the link 13 causes the lever 10 to tilt thereby moving the link 14 upwardly which in turn causes the slide 7 to move into the casing. If the operating lever 15 be depressed, the part 15^a of the lever engages the top of the opening 7^f, raising the slide 7. The slide 7 carries with it the link 14 causing the lever 10 to rock about its pivot moving the link 13 downwardly thus pulling the slide 6 downwardly into the casing. Whenever the lever is released, the spring 9 will act to move the slides outwardly from the casing to move the bolts to locking position.

The mechanism so far described is old and well known, being disclosed in my Patent

No. 1,383,973 above referred to. The present invention consists in the provision of a stop device co-acting with one of the slides and adjustable to limit the movement of the slides in the direction in which they are urged by the spring 9 so that by adjusting the stop device, the lock bolts may be retained in any position desired against movement toward locking position. To this end the slide 7 is provided within the casing 8 adjacent the bottom thereof with a lateral projection 7^h which is adapted to engage with the upper end of a set screw 19 which is in threaded engagement with an opening in the lower end of the casing. The lever 15 may be actuated in either direction to release the lock bolts and while the slides are held in lock releasing position the set screw 19 may be readily adjusted by hand into engagement with the underside of the projection 7^h to positively retain the bolts in retracted position. When the lock operating mechanism is so held by the set screw 19, the lever 15 will swing downwardly against the side of the door and when actuated will not act upon the slide to exert thrust upon the stop member since the projection 13^a will be spaced sufficiently from the top of the opening 7^f to allow the lever to swing freely. The operation of the lever 15 in either direction, however, would be to further retract the latch bolts and not to exert thrust against the stop member.

Referring to Fig. 4 of the drawing, the invention is shown applied to an actuator 100 for a mortised door lock 20 which is provided with the usual latch 21 and latch operating trip 22, exposed at the bottom edge of the latch casing. The lock actuator is in the form of a casing 23 secured to a side 105 face of the door below the lock casing. Within the casing 23 there is a vertically movable slide 24 which has a projection 25 at its upper end which cooperates with the trip 22 to release the latch. The slide 24 is 110 pressed downwardly in the casing by a compression spring 26 seated in a recess in the slide and acting between the slide and the top casing. The slide is actuated by means of a lever 27 pivoted to the casing and having a projection 27^a extending into a slot 24^a in the slide. Engaging the top of the projection 27^a is a cushion block 28 which is 115 slidable in the slot 24^a and is pressed into engagement with the top of the projection 27^a by means of a compression spring 29 mounted in the slot and acting between the cushion block 28 and the top of the slot. The projection 27^a is normally held against the bottom of the slot 24^a by means of the 120 compression spring 29. For securing the slide 24 in its lock releasing position, the casing 23 is extended at its lower end to provide space for a vertically disposed set screw 30 which engages the lower end of the slide. 125

By adjusting the set screw 30 the slide 23 may be positively held with the projection 25 thereof in engagement with the trip 22 to hold the latch 21 in retracted position.

5 In Figs. 5 and 6 of the drawing, there is shown a modified form of the invention in which both the upper and lower locking bolts are moved to releasing position by movement in an upward direction. In this modification there is a casing 31 similar to the casing 23 in Fig. 4 in which there is mounted a slide 32 which has upper and lower slotted portions 32^a and 32^b connected by a narrower slot in which is positioned the projection 27^a of a lever similar to the lever 27 shown in Fig. 4. The slide 32 has bolts 33 and 34 connected to its upper and lower ends, the bolt 33 coacting with the top of the door casing and the bolt 34 coacting with a stop device in the floor. Between the upper end of the slide 32 and the top of the casing there is a coil spring 35 which acts to force the slide in a downward direction to move the bolts into locking position. In this 20 modification the actuating lever is cushioned in both directions. In the slot 32^a there is mounted a cushioning block 36 which is held in engagement with the top of the projection 27^a by means of a compression spring 37 and in the upper end of the slot 32^b there is a cushion block 38 which is held in engagement with the bottom of the projection 27^a by means of a compression spring 39. The blocks 36 and 38 are normally held seated 25 against the lower and upper ends of the slots 32^a and 32^b, the length of the narrow slot between the slots 32^a and 32^b being just sufficient to accommodate the projection 27^a of the lever, thus when pressure is exerted upon 30 the lever in either direction, this pressure is transmitted to the slide through a cushioning spring which prevents shocks and excessive pressures upon both the lever and the parts of the lock. The upper bolt 33 is designed 35 to move to locking position in a downward direction so that the door is locked at the top and bottom by moving the slide in one direction. To this end the bolt 33 is provided with an inwardly projecting hook 40 at its 40 upper end which when the door is closed enters a slot 41 in an angle lock plate 42 secured to the top member of the door casing. When the lock bolt 33 is moved downwardly 45 the hook 41 engages with the plate 42 beneath the slot to lock the door against opening movement. To provide means for retaining the lock bolts in retracted position, the casing 31 is extended at its lower end to 50 provide space for a vertical set screw 43 adapted to be adjusted into engagement with the lower end of the slide 32 when the same is held in lock releasing position. The lower cushioning device engaging the bottom of the projection 27^a of the lever serves to 55 cushion the thrust of the lever against the

slide in a downward direction against the end of the set screw 43 so that both the lever and the set screw are protected against injury which might occur upon violent actuation of the actuating lever. The screw 43 70 may be, as shown in Fig. 5, in the form of a threaded plug with a socket in its outer end adapted to be engaged by a small socket wrench or key. This form of set screw has the advantage that unauthorized persons 75 cannot readily tamper with the stop device.

Having described my invention, I claim—

1. A lock actuating device comprising a casing, a lock operating slide movable in the casing, a lever pivoted to the casing and 80 having a part cooperating with the slide to shift the same in a direction to release the lock, and an adjustable stop member interposed between the casing and slide and adapted to limit the movement of the slide 85 from its lock releasing position.

2. A lock actuating device comprising a casing, a slide movably mounted in the casing and adapted when moved in one direction to release the lock, an actuating means 90 carried by the casing and adapted when operated to shift the slide toward lock releasing position, and a stop member interposed between the casing and slide and adjustable in the direction of movement of the slide to 95 limit the movement of the slide.

3. A lock actuating device comprising a casing, a slide movably mounted in the casing and adapted when moved in one direction to release the lock, actuating means for 100 shifting the slide, and a set screw disposed longitudinally of the slide and interposed between the casing and slide to limit the movement of the slide.

4. A lock actuating device comprising a 105 casing, a lock operating slide movable in the casing, a spring acting on the slide to shift the same in one direction, a manually operable lever adapted to shift the slide in opposition to the spring, and a set screw disposed longitudinally of the slide and adapted to be adjusted to hold the slide in lock 110 releasing position.

5. In a door lock releasing device, a casing secured to a side face of the door, a vertically movable lock actuating slide in said casing, an actuating lever for the slide carried by the casing, and a vertically disposed set screw at the lower end of the casing and interposed between the casing and slide and 120 adjustable to hold the slide against movement in one direction from any of its positions within the casing.

6. The combination with a door lock having a bolt carried by the door and engageable with the door casing, of lock actuator comprising a casing secured to a side face of the door and having a slide therein operatively connected to the bolt, an actuating lever carried by the casing and adapted to 125

actuate the slide, a spring acting on the slide for moving the same in one direction and a set screw carried by the casing and adjustable into engagement with the slide to hold the same in lock releasing position in opposition to the spring.

7. The combination with a double bolt door lock in which bolts carried by the door are movable into engagement with the door casing at the top and bottom of the door, of lock operating means comprising a spring actuator acting to yieldingly press the bolts toward locking position and a manually operable actuating device comprising a slide having a connection with the bolts and through which the spring acts, means for manually operating the slide in opposition to the spring to release the lock, and a set screw adjustable in the direction of movement of the slide and interposed between the slide and casing to hold the slide in lock releasing position in opposition to the spring.

8. A lock operating mechanism comprising a casing, a slide in the casing adapted to release the lock, a normally operable actuator for the slide, cushioning means interposed between the actuator and slide, a spring acting on the slide in a direction to move the same away from lock releasing position, and a stop member interposed between the slide and casing, said stop member being adjustable longitudinally with respect to the slide and adapted to limit the movement of the slide away from lock releasing position.

9. A lock operating mechanism comprising a casing, a lock actuating slide in said casing, a spring acting on the slide to move the same in one direction, a lever carried by the casing and having a part adapted to actuate the slide, and cushioning means inter-

posed between the lever and slide through which the lever acts upon the slide when moved in either direction.

10. A lock actuating mechanism comprising a casing, a lock actuating slide in said casing, an actuating lever pivoted to the casing and having a part projecting into the casing into operative engagement with the slide, and compression springs carried by the slide on opposite sides of the projecting part of the lever, through which the thrust of the lever in either direction is transmitted to the slide.

11. A lock actuating mechanism comprising a casing, a lock actuating slide in the casing, a stop member adjustable longitudinally of the slide and interposed between the slide and casing to limit the movement of the slide in one direction, an operating lever for moving the slide and adapted to exert pressure through the slide upon the stop member, and cushioning means interposed between the lever and stop member to prevent transmission of excessive pressures from the lever to the stop member.

12. A lock actuating mechanism comprising a casing, a lock actuating slide in the casing, a stop member adjustable longitudinally of the slide and coacting with the slide and casing to limit the movement of the slide in one direction, a lever pivoted to the casing and having a part co-acting with the slide to shift the same in either direction, and a spring cushion carried by the slide in position to be engaged by said part of the lever when the lever is moved in a direction to move the slide in the direction in which its movement is limited by the stop.

In testimony whereof I hereunto affix my signature.

WILLIAM B. BOLLES.
